ELEVATOR TOUCH BUTTON PANEL

Morrison John Brounn, Flushing, N. Y., assignor to Otis Elevator Company, New York, N. Y., a corporation of New Jersey

Application April 30, 1956, Serial No. 41,282

Term of patent 14 years

(Cl. D26—13)

FIG. 1

FIG. 2

Figure 1 is a front perspective view of an elevator touch button panel showing my new design, the dash lines shown being for illustrative purposes only, and

Figure 2 is a sectional view thereof taken on line 2—2 of Figure 1.

I claim:

The ornamental design for an elevator touch button panel, substantially as shown and described.
